UNITED STATES PATENT OFFICE.

JAMES SETCHFIELD, OF PORTLAND, OREGON, ASSIGNOR OF ONE-HALF TO THOMAS J. QUIRK, OF PORTLAND, OREGON.

FIREPLACE AND SCREEN.

Application filed July 28, 1924. Serial No. 728,749.

To all whom it may concern:

Be it known that I, JAMES SETCHFIELD, a citizen of the United States, residing at Portland, in the county of Multnomah, 5 State of Oregon, have invented certain new and useful Improvements in Fireplaces and Screens; and I do hereby declare the following to be a full, clear, and exact description of the invention, such as will enable 10 others skilled in the art to which it appertains to make and use the same.

This invention relates to new and useful improvements in fireplace devices and particularly to screens therefor.

15 One object of the invention is to provide a screen for a fireplace which is arranged to be folded for positioning at one side of the fireplace, the fireplace being constructed to receive the folded screen so that said 20 screen will be concealed from view.

Another object is to provide a receptacle disposed within a recess in the side of the fireplace, into and from which a foldable screen may be quickly and easily moved, an 25 ornamental closure being provided for the receptacle to conceal the screen when folded and within the receptacle.

A still further object is to provide a receptacle of this character, and a foldable 30 screen, with coperating means therebetween which guide the screen into and out of the receptacle, but wherein said means prevent the screen being entirely removed from the receptacle.

35 Other objects and advantages will be apparent from the following description when taken in connection with the accompanying drawing.

In the drawing:

40 Figure 1 is an elevation of a fireplace showing the invention applied thereto, the screen being in position in front of the fireplace.

Figure 2 is an enlarged horizontal sectional view on the line 2—2 of Figure 1, just above the screen within the receptacle.

Figure 3 is a vertical transverse sectional view on the line 3—3 of Figure 2.

Figure 4 is a fragmentary horizontal sectional view on the line 4—4 of Figure 3.

Referring particularly to the accompanying drawing, 10 represents the side portions of the fireplace 11, and formed through the front face of each side portion 10 is a recess 12. This recess extends back into the

side 10 to the required distance, and is of a height somewhat greater than the height of the foldable screen 13, and comparatively narrow. In the recess there is disposed a metal box or receptacle 14, which snugly fits 60 within the recess, the front end being open and provided with a peripheral flange 15 which may be secured to the face of the fireplace by cement, or other well known means, for maintaining the box within the recess. 65 Secured to the interior of the box, and spaced a short distance above the bottom thereof, is a floor 16, and located on the upper face of the floor, adjacent and parallel with one side wall of the box, is a vertical 70 flange or rib 17, which combines with said side wall to form a channel, for the reception of the downwardly extending pin 18 carried by the lower side of the inner end of the innermost section of the screen. 75 Secured to the upper portion of the interior of the box, and arranged in parallel relation to the flange or rib 17, is a rod 19, and slidably between this rod and the adjacent side wall of the box, is the upwardly extending pin 80 20 carried by the upper portion of the inner end of the said innermost screen section. It will be noted, upon reference to Figure 2, that the forward end of the rod 19 is turned laterally and is secured in the side wall of 85 the box. This laterally turned portion forms a stop to prevent the pin 20 passing out of the box, while a transverse member 21, between the flange 17 and the side wall of the box, serves as a stop for the pin 18. 90 Thus the innermost section of the screen is prevented from being pulled completely from the box.

Secured to the inner end wall of the box, below the floor 16, and adjacent the top wall of the box, respectively, are coil springs 95 22 and 23. A closure plate or door 24 is disposed against the front end of the box, and on the upper and lower portions of its inner face there are mounted the horizontally extending apertured ears 25 and 26, to which are connected the respective forward ends of the coil springs 22 and 23, said springs exerting pull on the door to maintain the same in proper closing relation to the open front end of the box. The outer face of this door may be ornamented as desired, and is provided with a knob or other suitable handle 27, which is adapted to be grasped to withdraw the door from the 100 105 110

front of the box, and thereby permit the screen being pulled therefrom and unfolded into proper position before and across the fireplace.

5 It will be noted that the floor 16 terminates a short distance inwardly of the front or open end of the box, whereby a space 16' is provided to receive the legs 28 of the outer sections of the screen 13, when said 10 screen is folded and slipped into the box. When the screen is thus disposed within the box, the springs 22 and 23 draw the door or plate 24 into firm covering position at the open end of the box, thus completely concealing the folded screen from view.

15 It will be understood that the parts above described are duplicated at the other side of the fireplace, so that one half of the screen is arranged to be supported or stored by 20 one box, and the other half by the other box. When the screen halves are withdrawn from the boxes, and stretched across the front of the fireplace, the abutting sections of the halves are detachably secured together 25 by means of the hooks 29 and eyes 30, carried respectively by said abutting sections.

What is claimed is:

1. The combination with a fireplace having a recess in its face, of a foldable screen 30 movable into and out of the recess, means in the recess engaged by one of the screen

sections for guiding the screen into and out of the recess, means associated with the guiding means for limiting the outward movement of the screen from the recess, and a resiliently held closure for the recess.

35 2. The combination with a fireplace having a recess in its face, of a receptacle mounted in the recess, a foldable screen movable into and out of the recess, guiding rails 40 in the recess, means on one of the screen sections engaged with said rails, and means on the rails for engagement by the screen carried means to limit the outward movement 45 of the screen from the recess.

50 3. The combination with a fireplace having a recess in its front face, of a receptacle mounted in the recess, a foldable screen movable into and out of the receptacle, said screen including an innermost section, guiding rails extending longitudinally of the upper and lower portions of the receptacle, 55 projections on the innermost section cooperating with said rails in the receptacle for guiding the section into and out of the receptacle, and stop means on the outer ends of the rails for engagement by the said projections to prevent complete removal of the screen from the receptacle.

In testimony whereof, I affix my signature.

JAMES SETCHFIELD.
